UNITED STATES PATENT OFFICE.

FRANK G. HOLMES, OF TRENTON, NEW JERSEY.

DESIGN FOR A PLATE OR SIMILAR ARTICLE.

Application filed March 31, 1924. Serial No. 9,122. Term of patent 14 years.

To all whom it may concern:

Be it known that I, FRANK G. HOLMES, a citizen of the United States, residing in Trenton, in the county of Mercer and State of New Jersey, have invented a new, original, and ornamental Design for a Plate or Similar Article, of which the following is a specification, reference being had to the accompanying drawing, forming part thereof.

The figure is a plan view of a plate showing my design.

I claim:

The ornamental design for a plate or similar article as shown.

FRANK G. HOLMES.

Witnesses:

WM. H. CLAYTON,
EDWIN T. FITZGEORGE.
